UNITED STATES PATENT OFFICE.

WILLIS A. SCHLEIT, OF SYRACUSE, NEW YORK.

DRAFT-REGULATOR FOR HEATERS.

1,310,505.

Specification of Letters Patent. Patented July 22, 1919.

Application filed August 20, 1915. Serial No. 46,443.

To all whom it may concern:

Be it known that I, WILLIS A. SCHLEIT, a citizen of the United States of America, and resident of Syracuse, in the county of Onondaga, in the State of New York, have invented new and useful Improvements in Draft-Regulators for Heaters, of which the following, taken in connection with the accompanying drawings, is a full, clear, and exact description.

This invention relates to certain improvements in heating apparatus, and more particularly to draft regulators for heaters, such as hot water heaters where it is desired to maintain a substantial uniformity of temperature.

Hot water heaters constructed as herein set forth are particularly advantageous for use in connection with hot water heating systems for incubators and the like, in which the successful operation of the apparatus depends upon a close regulation of the heating means.

The primary object, therefore, of the invention is to provide an improved construction of heater operating upon improved methods, in which the draft is susceptible of exceedingly close and automatic regulation for supplying heating fluid at substantially uniform temperature to a fluid heating system.

Another object is to so construct the regulating parts that they may be readily moved from operable position, without detachment, to allow fuel to be supplied to the heater.

Other objects and uses will appear from the following description taken in connection with the accompanying drawings, in which—

40 Figure 1 is a top plan view of the heater. Fig. 2 is a side elevation partly in section, of the same.

Fig. 3 is a cross section on line 3—3, Fig. 1.

The heater, as shown, comprises a combustion chamber —1— surrounded by an upright boiler or water jacket —2— connected to a water circulating system (not shown) by pipes —3— and —4—. The jacket —2— is closed at the top by a partition wall —5— having a central opening forming a draft port —6— leading from the combustion chamber —1— to a smoke chamber —7— formed by a hollow top section —8— connected, in the construction shown, by bolts 55 —9— to the partition —5—.

The section —8— is provided with a

smoke outlet —10— and an opening —11— adapted to be closed by a suitable lid —12— having, in this instance, a series of check ports —13— allowing communication between the smoke chamber —7— and the atmosphere. The lid is provided with a depending circumferential flange —14— bordering the outer edge of the check ports —13— and projecting into the smoke chamber —8— and spaced a short distance from, and of substantially the same diameter as, the upper edge of the combustion chamber forming the draft port —6—.

The lid is further provided with a suitable depending boss —15— substantially concentric with, and within, the flange —14— and provided with bearings for a connecting rod —16— carrying a valve —17— and operably connected to a jointed lever —18— by link —19—. The valve —17— is slidable upon the rod —16— and is prevented from removal by a suitable nut —20—, and is movable between the upper edge of the combustion chamber —1— and the lower edge of the flange —14— for controlling not only the communication of the draft port —6— with the smoke chamber —7— and with the atmosphere through check ports —13—, but also for controlling communication between the check ports and the smoke chamber —7—.

The jointed lever —18— is provided with a suitable adjustable weight —21— so regulated as to normally hold the valve —17— in contact with the lower edge of the flange —14— to shut off communication between the smoke chamber —7— and the atmosphere through check ports —13—.

The operation of lever —18— is controlled by any suitable thermostatic device, indicated at —22—, upon which the lever may be pivotally mounted and adapted to be actuated by a bearing —23— for rocking the lever about its pivot as the temperature of the water in the pipe —4— rises. As the temperature of the water in the boiler —2— and pipe —4— rises, the bearing —23— rocks the lever —18— about its pivot allowing the valve —17— to move downwardly toward closed position with respect to the draft port —6—, and at the same time allowing communication of the combustion chamber and the smoke chamber through check ports —13—. The temperature of the water may rise to such a point that the valve —17— will move downwardly to a point

sufficient to entirely close the draft port —6—.

By this movement of the valve —17—, controlling simultaneously the effective communication of the draft port —6— and check ports —13—, both with each other and with the smoke chamber —10—, a very close and automatic regulation of the combustion and, therefore, the temperature of the heating fluid, in accordance with the temperature of said fluid, is obtained.

The lever —18—, as heretofore stated, is a jointed lever, to allow the lid —12— and valve —17— to be raised from operable position with respect to the heater, as shown in Fig. 3, so that fuel may be placed in the combustion chamber through the opening —11— and draft port —6— without removing or detaching any of the regulating parts. For this purpose the lever comprises a pair of arms —24— and —25— and a connecting member —26— having spaced flanges upon opposite edges thereof, the arm —25— positioned between the spaced flanges upon the lower edge and connected thereto by screws —27—, and the arm —24— positioned between the spaced flanges upon the opposite edge and pivotally connected to one pair of said flanges, as by bolts —28—, so that the arm —24— is free to move upwardly about its pivot with respect to arm —25— and connecting member —26— but is normally held in contact with said member by its own weight and by the weight of the lid —12— and valve —17— supported thereby.

The arm —25— is pivotally mounted upon the lugs —29— projecting upwardly from the housing of the thermostatic device —22—.

Although I have shown and described one particular construction, form and arrangement of the parts, I do not desire to limit myself to the same, as many changes may be made in the details of form, construction, arrangement and operation without departing from the spirit of this invention as set forth in the appended claims.

What I claim is:

50. 1. In a heater, a combustion chamber, a smoke chamber, a draft port constituting means of communication between the smoke chamber and the combustion chamber and having an upwardly facing valve seat, the smoke chamber provided with a fuel feed opening, a lid for the opening, said lid provided with a check port and formed with a tubular depending flange having a downwardly facing valve seat, and a valve movable between said valve seats and controlling the draft and check ports.

65. 2. In a heater, a combustion chamber, a smoke chamber, a draft port constituting means of communication between the smoke chamber and the combustion chamber and

having an upwardly facing valve seat, the smoke chamber provided with a fuel feed opening, a lid for the opening, said lid provided with a check port and formed with a tubular depending flange having a downwardly facing valve seat, a valve movable between said valve seats and controlling the draft and check ports, and thermostatically controlled means for actuating the valve.

3. In a heater, a combustion chamber, a smoke chamber disposed above the combustion chamber, a fuel feed draft port between the combustion chamber and the smoke chamber and formed with an upwardly facing valve seat, a removable lid for the smoke chamber having an opening therethrough and a depending tubular flange around the opening forming a check port for the smoke chamber and having a downwardly facing valve seat, a valve movable between the draft port and the check port, and thermostatically controlled means for actuating the valve.

4. In a heater, a draft port, a lid having a substantially tubular depending portion aligned with the draft port and adapted to form a check port, and a valve controlling both of said ports.

5. In a heater, a combustion chamber and a smoke chamber, a tubular extension projecting upwardly into the smoke chamber and forming a fuel feed draft port between the smoke chamber and the combustion chamber, a movable lid for the smoke chamber having openings therethrough, and a depending substantially tubular flange around the openings forming a check port for the smoke chamber, and a valve movable between the draft port flange and the check port flange and adapted to control both ports.

6. In a heater, a combustion chamber and a smoke chamber, a tubular extension projecting upwardly into the smoke chamber and forming a fuel feed draft port between the smoke chamber and combustion chamber, a movable lid for the smoke chamber having openings therethrough and a depending substantially tubular flange around the openings forming a check port for the smoke chamber, a valve movable between the draft port flange and the check port flange and adapted to control both ports, and a rod carrying the valve, the valve adapted to move the lid from seated position when the rod is raised beyond a predetermined position.

7. In a heater, a combustion chamber and a smoke chamber, a tubular extension projecting into the smoke chamber and forming a fuel feed draft port with an upwardly facing valve seat, a removable lid forming a portion of the wall of the smoke chamber and having a tubular depending portion aligned with said tubular extension and form-

ing a check port, and a valve movable between and controlling both ports.

8. In a heater, a combustion chamber and a smoke chamber, a tubular extension projecting into the smoke chamber and forming a draft port with an upwardly facing valve seat, a removable lid forming a portion of the wall of the smoke chamber and having a tubular depending portion alined with 5 said tubular extension and forming a check port, and a valve movable between and controlling both ports, said valve having an axially extending marginal flange within which said tubular depending portion is 10 adapted to fit, said lid being movable from its position as a portion of the wall of said smoke chamber by movement of said valve beyond a predetermined point whereby the draft port may be exposed for the insertion 15 of fuel.

9. In a heater, a combustion chamber, a smoke chamber, a draft port constituting means of communication between the combustion chamber and the smoke chamber and 20 formed with an upwardly facing valve seat, said smoke chamber provided with a fuel feed check port and formed with a tubular depending flange about the port, said flange 25

having a downwardly facing valve seat and a valve movable between said valve seats and 30 controlling the draft and check ports.

10. In a heater, a lever comprising two arms and a connecting member rigidly secured to one of said arms and pivotally connected to the other arm and having a seat 35 for said last named arm in advance of said pivot, permitting breaking of the lever in one direction only and a valve secured to said last named arm.

11. In a heater, a lever comprising two 40 arms and a connecting member rigidly secured to one of said arms and pivotally connected to the other arm and having a seat for said last named arm in advance of said pivot, permitting breaking of the lever in 45 one direction only and means mounted on said connecting member for varying the angular disposition of said arms and a valve connected to the arm pivoted to said connecting member.

In witness whereof I have hereunto set my hand this 7th day of June, 1915.

WILLIS A. SCHLEIT.
